UNITED STATES PATENT OFFICE.

ERNST TOENNIESSEN, OF UNTERHAUSEN, GERMANY.

FOUR-CYLINDER DRAWHEAD.

Application filed November 17, 1925, Serial No. 69,718, and in Germany December 12, 1924.

This invention relates to improvements in and relating to four-cylinder draw-heads for high draft with special weighting of the top rollers situated in front and behind the pair of drawing rollers. The invention essentially characterizes itself in that, for the two top rollers, situated in front and behind the pair of drawing rollers, a weight-controlled saddle which engages with a yoke, is journalled in such a manner, that in the open or raised position of said saddle, the front top roller stands under the entire weight, the two following top rollers being simultaneously laid free.

The special weighting manner permits, in maintaining the weighting of the front top roller, which works together with the feed cylinder, to simultaneously relieve the top roller situated behind the pair of drawing rollers, allowing thus, without interruption of service or breaking of the thread, the easy access to the latter top roller and also of the light drawing roller which may thus be comfortably cleaned.

The invention is clearly illustrated, by way of example, on the accompanying drawing, in which:

Fig. 1 is a schematic view of the draw-head with weighting device, the saddle being in the closed or lowered position.

Fig. 2 is a similar view as Fig. 1, the saddle being in the open or raised position.

The yoke B extends partly over and around the rollers of the draw frame and is held in a downward direction by a weight or spring G and engages with its fork-shaped head into a pin 1^a on the nose 3 of the saddle S journalled on the front roller a. The saddle is so mounted on the roller that it is prevented from being disengaged therefrom when swung forwardly to the position shown in Fig. 2. In this manner the top rollers a and b are firmly pressed upon their corresponding bottom rollers I and III. Owing to the present weighted lever system, the diameter of the top roller b may be considerably reduced in opposition to when own weighting is applied and consequently it will also be possible to considerably reduce the distance of the point of contact between rollers II and c, and III and

b, in opposition to when own weighting is applied.

This reliably acting weighting further attains:

(1) That between rollers III, b and IV, d an effective preliminary draft of whatever degree may be applied, and

(2) That the fibre tuft, projecting from rollers III, b in forward direction, is securely gripped and further more than 50% of the entire fibres between the rollers II, c are held by rollers III, b. The pair of drawing rollers II, c guides the greatest part of the fibres still freely travelling about in the draft-field, so that, even at very high degrees of draft, uniform yarn is obtained.

By swinging the saddle to the position shown in Fig. 2, the top drawing roller c and the top roller b can be cleaned during the spinning, and when the saddle is in said position the weighting of the top feed roller a is maintained.

In the open or raised position of the saddle shown in Fig. 2 the head of the yoke B butts against the saddle S and arrests and prevents further swinging of the saddle.

The lever may be weighted directly or indirectly without however departing from the scope of the invention.

I claim:

1. In combination with a four-cylinder draw-head, a weighting device comprising a weighted yoke extending over the front top pressure roller of the draw-head, and a saddle journalled on the front top roller and loosely connected with the yoke whereby the saddle can be swung into open position and with the said front top pressure roller remaining weighted.

2. In combination with a four-cylinder draw-head, a weighted yoke extending over the front top pressure roller of the draw-head and a saddle journalled on the top front roller, and means for pivotally and detachably connecting the saddle with the extreme end of the yoke, said end serving as a stop to limit the outward swinging movement of the saddle.

3. In combination with a four-cylinder draw-head a weighting device comprising a weighted yoke extending over the front top

pressure roller of the draw-head and provided with a forked shaped end, and a saddle journaled on the front top pressure roller and provided with a pin engaged by 5 the forked shaped end of the yoke.

4. In combination with a four-cylinder draw-head, a weighting device comprising a yoke extending over the front top pressure roller of the draw-head and provided with a

forked head, and a saddle journaled on the 10 front top roller and provided with a nose and a projection swung as a handle, and a pin in said nose with which the forked head of the yoke engaged.

In testimony whereof I have signed my 15 name to this specification.

ERNST TOENNIESSEN.
